VACUUM CLEANER

Dewey M. Dow, Toledo, Ohio, assignor to Air-Way Electric Appliance Corporation, Toledo, Ohio, a corporation of Delaware

Application August 25, 1936, Serial No. 97,777

4 Claims. (Cl. 15—157)

This invention relates to vacuum cleaners of the type illustrated in my pending applications, Serial Number 66,882, filed March 3, 1936, Serial Number 74,012, filed April 13, 1936, Serial Number 84,072, filed June 8, 1936, and Serial Number 92,712, filed July 27, 1936. The present application constitutes a continuation in part of those applications and the disclosures of those applications are hereby incorporated in and made a part of the present application.

An object of the present invention is to provide a novel carpet spacing and guard member for a vacuum cleaner floor tool. A further object is to provide a guard member for a floor tool of the type contemplated in the aforesaid pending applications. Another object is to provide such a guard in combination with a novel floor tool bottom plate.

Another object is to provide a guard member, formed in a single piece, yet providing two spaced guard cross bar elements in the mouth of the floor tool. Another object is to provide a guard member embodying two spaced cross bar elements, which guard is held in place by spring tension within itself. Another object is to provide a spring-held guard which will not become accidentally displaced or detached under pressure of the carpet. Another object is to provide a guard which is of a very simple, durable, and exceedingly inexpensive construction. Another object is to provide, in combination with a cleaner of the type under consideration, a novel wheel adjusting mechanism.

Further objects will appear in the perusal of the following detailed description of the invention in connection with the accompanying drawing in which:

Fig. 1 is an inverted plan view of a vacuum cleaner embodying the invention.

Fig. 2 is a transverse sectional view through the agitator chamber, the agitator, and guard, taken on the line 2—2 of Fig. 1.

Fig. 3 is a sectional view taken on the line 3—3 of Fig. 2.

Fig. 4 is a sectional view taken on the line 4—4 of Fig. 1, showing the wheel adjusting mechanism of the cleaner, and

Fig. 5 is a side elevation of the wheel adjusting mechanism.

Briefly describing the general features of the type of cleaner under consideration, it is pointed out that the floor tool has an agitator chamber 18 merging into a rearwardly extending throat 11 (Fig. 2) which in turn forks into a pair of spaced

conduits 12 which lead to the opposed dual inlets of the fan (not shown herein).

The casting which forms the chamber 10 and the top and sides of the throat 11, is open at its bottom from the forward wall of the chamber 10 to the forward edges 13 of the conduits 12. The space from the edges 13 to the rear extremity of the suction mouth 14 is closed by a bottom plate 15 of stamped sheet metal. The bottom plate follows the contour of the side walls 16 of the throat 10 and its rear region is cut away to fit the forward region of the side walls of the conduits 12.

Wheel sockets 17 are formed integrally with the throat 11 and front wheels 18 are mounted therein on studs 19 which are secured in the end walls of 15 the sockets 17 by threaded nuts 20.

The plate 15 is detachably secured in place by screws 21 threaded into bosses 22 formed integrally with the side walls 16 of the throat 11.

The forward edge region of the plate 15 is bound 20 with a channel 23 of stainless steel which forms the rear carpet engaging lip of the mouth 14. An L-shaped strip 24 is secured as by means of screws 25 to the forward wall of the chamber 10 and forms the support for the rubber bumper 26 extending around the floor tool. The forward lip member 27 of stainless steel is welded to the lower face of the strip 24 and forms the forward lip of the suction mouth 14.

The guard G (Fig. 3) is formed of spring wire 30 and comprises a central web portion 28 formed at its ends with a pair of U-bends 29, and cross bars 30 form continuations of said U-bends 29, and project substantially at right angles to the web portion 28. The ends of the cross bars 30 are formed 35 into hooks 31 opening outwardly away from each other.

Headed buttons 32 are riveted at 33 in the strip 24 and covered from beneath by dimples 34 in the lips 27. The dimples 34 also prevent the buttons 40 32 from working out of position. Buttons 32a extend through the three thicknesses of metal comprising the bottom plate 15 and lips 23, and are riveted therein. The U-bends 29 of the guard G receive the buttons 32 and the hooks 31 of the 45 cross arms 30 receive the buttons 32a. The members 29 and 31 are retained by the heads of the buttons 32 against slipping axially from the buttons 32 and 32a. The arms 30 normally tend to assume a position such as that illustrated on the 50 left hand side of Fig. 3 so that when hooked to the buttons 32, they engage the buttons under spring tension and will not become disengaged. The hooks 31 hold the U members 29 against being released from the buttons 32.

In applying the guard, the U-bends 28 are first slipped between the heads of the buttons 32 and the front wall of the chamber 10, and are thence drawn rearwardly until they are received between the heads of the buttons 32 and the strip 24, in contact with the reduced neck portion of the buttons. The hooks 31 are then sprung toward each other, passed over the heads of the buttons 32a, thence moved into contact with the lips 23 and thence allowed to spring into position embracing the reduced necks of the buttons 32a. In this position they will be supported between the heads of the buttons 32a against forward movement such as might be occasioned by the forward pressure of the carpet against the cross arms 30.

The rear wheels 48 are mounted on stub shafts 41 riveted in the side flanges 42 of the rear bracket 43. The forward region of the bracket 43 is provided with a U-bend 44 which receives the mounting shaft 45. The latter has a key slot 46 receiving a key 47 punched in the U-bend 44. A screw bolt 48 extends through the respective sides of the U-bend 44 and engages the shaft 45 to securely hold the bracket in place on the shaft 45.

The shaft 45 is mounted in pillow blocks 49 formed in the conduits 12 and a bearing cap 50 is secured by screws 51 to said pillow blocks 49. One end of the shaft is extended and carries an adjusting arm 52 in the end of which is mounted a spring-pressed plunger 53 engageable in openings 54 (Fig. 5) in the keeper 56. The keeper 56 is secured by screws 57 to the rear flanges 58 of the conduit 12. The screws 57 also serve to secure the flanges 58 to the elbows 59 which connect the conduits 12 to the fan (not shown).

The member 60 shown in Fig. 1 is a member for the attachment of auxiliary suction tools or extension hose and is normally closed by a cap 61 carried by a spring-pressed plunger 62 mounted in the end of a lever arm 63. The arm 63 is mounted on a shaft 64 journalled in bosses 65 in the wheel sockets 17.

A gate valve 66 is secured to the shaft 64 and is adapted when moved to a vertical position to close off the throat 11, so as to direct the suction to the member 60. Removal of the cap 61 thus automatically effects closing of the valve 66.

I claim as my invention:

1. In a vacuum cleaner having a suction mouth whose pair of lips lie substantially in a horizontal plane in combination, a pair of spaced headed buttons secured to each lip, and a guard comprising a web portion, a pair of cross arms extending at right angles thereto, a pair of U-bends in the web portion, receiving one pair of said buttons, and a pair of hooks in the free ends of the cross arms, opening outwardly and receiving the other of said pair of buttons. 5

2. In a vacuum cleaner floor tool whose suction mouth is defined by a pair of lips lying substantially in a horizontal plane with a pair of spaced headed buttons secured to each lip in combination, a guard comprising a web portion, a pair of cross arms extending at right angles thereto, a pair of U-bends in the web portion, said U-bends opening in directions parallel to said cross arms, receiving one pair of said buttons, and a pair of hooks in the free ends of the cross arms, opening outwardly and receiving the other of said pair of buttons. 15 20

3. In a vacuum cleaner floor tool whose suction mouth is defined by a pair of lips lying substantially in a horizontal plane with a pair of spaced headed buttons secured to each lip in combination, a guard comprising a web portion, a pair of cross arms extending at right angles thereto, a pair of U-bends in the web portion, 30 receiving one pair of said buttons, and a pair of hooks in the free ends of the cross arms, opening outwardly and receiving the other of said pair of buttons, said cross arms being formed to spring apart and holding said hooks under tension in engagement with said buttons. 35

4. In a vacuum cleaner floor tool whose suction mouth is defined by a pair of lips lying substantially in a horizontal plane with a pair of spaced headed buttons secured to each lip in combination, a guard comprising a web portion, a pair of cross arms extending at right angles thereto, a pair of U-bends in the web portion, receiving one pair of said buttons, and a pair of hooks in the free ends of the cross arms, opening outwardly and receiving the other of said pair of buttons, said web portion lying above one of said lips. 40 45
